ATTORNEY.

UNITED STATES PATENT OFFICE.

THEODORE KAUFER, OF NEW YORK, N. Y.

ADJUSTABLE GARMENT-HANGER.

1,389,309.

Specification of Letters Patent. Patented Aug. 30, 1921.

Application filed October 15, 1920. Serial No. 417,098.

To all whom it may concern:

Be it known that I, THEODORE KAUFER, a citizen of the United States, and resident of New York, in the county of Bronx and State 5 of New York, have invented certain new and useful Improvements in Adjustable Garment-Hangers, of which the following is a full, clear, and exact specification.

This invention relates to garment hangers 10 of the type shown in my application for patent filed May 1, 1920, Ser. No. 378,055 and which has means for positively holding the collar and shoulders of a coat to the correct shape.

15 It is the object of the present invention to provide improved means for adjusting the garment hangers to fit different sizes of coats, to simplify the construction of such adjusting means and to render the same more 20 easy to adjust. The present construction of adjusting means is also designed as an improvement on the device disclosed in my application for patent filed July 31, 1920, Ser. No. 400,327.

25 The present invention will be first hereinafter described in connection with the accompanying drawings, which constitute part of this specification, and then more 30 specifically defined in the claims at the end of the description.

In the accompanying drawings, wherein similar reference characters are used to designate corresponding parts throughout the several views:—

35 Figure 1 is a side elevation of a garment hanger made substantially in accordance with this invention, part of the adjusting member being broken away.

Fig. 2 is a plan view of the hanger with- 40 out the supporting chains.

Fig. 3 is a detailed transverse section of the adjusting or connecting member drawn to a larger scale and showing one pair of lugs on the shoulder loops in engagement 45 therewith.

Fig. 4 is a central longitudinal sectional view of said connecting or adjusting member, and

50 Fig. 5 is a broken perspective view of the same.

The connecting or adjusting member of the hanger is indicated at 1 and is preferably made of a single piece of sheet metal bent to form a channelled central portion 7 having marginal or side flanges 2 having inwardly extending lugs 8 at the ends of said

member. Between said end lugs 8 the sheet metal piece is bent outwardly at the upper edges of the flanges 2 to form horizontal portions 3, then bent downward to form vertical portions 4 and finally bent inward to form horizontal portions 5, said portions 3, 4 and 5, with the flanges 2 forming tubular inclosures extending along the sides of the channel 7. In the flanges 2 spaced holes or 60 openings 10 are formed for adjusting purposes.

The hanger consists of shoulder loops 13 each having spring arms 12 provided with oppositely extending end lugs 11 adapted to 70 engage in the openings 10 in the flanges 2 of the connecting member 1, said arms extending below the end lugs 8 of said connecting member and being retained in proper alignment thereby. By pressing the arms 12 75 of the shoulder loops together, the lugs 11 may be easily disengaged from the openings 10 in which they have been arranged and placed in others of said openings for the purpose of changing the length of the hanger 80 to fit coats of different sizes. This adjustment may be very conveniently made on account of the fact that the channel 7 of the connecting member is open at the top so that the openings and lugs on the arms may be 85 seen during the adjustment and without the necessity of turning over the hanger as was the case with the construction disclosed in my prior application Ser. No. 400,327, filed July 31, 1920, already mentioned herein. 90

Said shoulder loops, which engage the shoulders of a coat when placed on the hanger, are formed of wire having sufficient resiliency to hold their ends 11 in engagement with the openings 10 in the sides of 95 the channel member. The lateral portions of the wire loops 13 have inwardly bent portions 14 constituting bearings for collar holding members 15 one of which is pivotally mounted on said bearings of each 100 shoulder member 13. The collar holding members 15 are also made of wire bent to form inwardly extending loops 16 and having their diverging side portions coiled at 17 around the bearings 14. The extremities 105 of said side portions extend beyond the coils 17 and terminate close to the outer ends of the loops 13 so as to form a continuous support for the collar and shoulders of a coat. The inner ends of the loops 16 are connected by chains 18, or other suitable flexible connections, to a ring 19 by means of 110

which the hanger may be supported from a nail or hook, not shown. When a coat is placed on the hanger in the usual way and the same supported from the ring 19, the weight of the garment will cause the collar holding members 15 to automatically turn on the bearings 14 so as to press into engagement with the inside of said collar where they will hold it in stretched position so that no wrinkles or creases can remain or be formed therein. Inasmuch as the collar holding members are carried by the shoulder members 13, the former will be necessarily adjusted with the latter so that the collar of every size of coat may be properly held as just described.

In order to support trousers or other garments from the hanger without interfering with the proper holding of the coat, an adjustable rod 20 depends from the ends of justable rod 20 depends from the ends of the loops 13 and extends across parallel to the hanger proper and at a suitable distance below the same. The rod 20 is preferably made of two pieces of wire having their inner ends overlapped and provided with sliding loops 21 each engaging the overlapping portion of the other piece while the outer ends of said rods or wires are bent around offset portions 22 in the ends of the loops 13. The rod 20 is thus adjustable with the main part of the hanger.

Having thus described my invention, what I claim as new and desire to secure by Letters Patent of the United States is:—

35 1. In a garment hanger, the combination with a central connecting member of channel form open at the top and having series of openings in its lateral walls, of shoulder members to extend into the ends of said channel member and provided with lateral

projections to engage any of said openings for adjusting the hanger to fit different sizes of garments, said connecting member being made of sheet metal having its middle portion bent to form the upwardly opening channel and its edge portions bent outwardly, downwardly and inwardly from the upper edges of the walls of the channel to form tubular portions for inclosing the outer ends of the projections on the shoulder members which extend through the openings in said channel walls.

2. In a garment hanger, the combination with a central connecting member of channel form open at the top and having series of openings in its lateral walls, of shoulder members to extend into the ends of said channel member and provided with lateral projections to engage any of said openings for adjusting the hanger to fit different sizes of garments, said connecting member being made of sheet metal having its middle portion bent to form the channel and its edge portions bent outwardly, downwardly and inwardly from the upper edges of the walls of the channel to form tubular portions for inclosing the outer ends of the projections on the shoulder members which extend through the openings in said channel walls, there being portions of the sheet metal at the ends of the channel bent inward from the upper edges of the walls of said channel so as to bridge the latter for retaining the shoulder members against swinging about said projections in said openings as a center.

In testimony whereof I have signed my name to this specification.

THEODORE KAUFER.
